UNITED STATES PATENT OFFICE

2,077,225

COMBUSTION ENGINE

Ernst Daiber, Berlin-Lichterfelde-West, Germany, assignor to General Electric Company, a corporation of New York

Original application June 20, 1932, Serial No. 618,373. Divided and this application September 9, 1936, Serial No. 100,003. In Germany June 26, 1931

3 Claims. (Cl. 123—173)

The present invention relates to combustion engines and more particularly to cylinder heads or covers for internal combustion engines, and the like, of the kind in which the inner and outer walls are made of a single cast structure of suitable material such as steel. The present application is a division of my application Serial No. 618,373, filed June 20, 1932, and assigned to the assignee of the present application.

10 One object of the invention is to provide a structure in which heat and casting stresses are substantially eliminated. Another object of the invention is to provide the structure with improved cooling means. A further object is to 15 provide a structure which permits the flow of scavenging air to the cylinders with the least drop in pressure.

For a better understanding of my invention, together with other and further objects there- 20 of, reference is had to the following description, taken in connection with the accompanying drawing, and its scope will be pointed out in the ap- pended claims.

In the drawing, Fig. 1 illustrates a vertical sec- 25 tional view of a cylinder head for a four-stroke Diesel engine embodying my invention, Fig. 2 is a horizontal cross sectional view taken along the lines AA in Fig. 1, and Fig. 3 is a horizontal cross sectional view taken along lines BB of Fig. 1.

30 Referring to the drawing, in greater detail, 5 represents the body or outer wall of the cylinder head, and 6 the inner walls, which define passages 7 for valve structures. The inner and outer walls of the structure are cast together by 35 a top plate 8 and an intermediate plate 9. The lower end of this structure is closed by a sepa- 40 rate plate 10 of suitable thin material such as forged iron, for example, having openings 11 therein, which register with the passages 7 for the valve structures.

According to my invention, I provide the base plate or closing member 10 with a raised edge or 45 annular projection 12 fitting into a recess or groove 13 on the lower face of the body. Leakage is prevented by soldering, welding or brazing the edge of the plate to the adjacent portion 50 of the body as indicated at 14. The lower edge 15 of the base plate 10 is separated from the cylinder wall 16 by a packing ring 17 for pre- 55 venting leakage between these parts. Bushings 18 are fastened to the base plate and inner walls and provide seats for valve structures to be inserted through the openings 19 and 20, and prevent leakage of fluid along the inner walls of the cylinder head. The intermediate plate or

partition 9, above-mentioned, defines with the adjacent inner and outer walls and with the base plate 10, a cooling chamber 21. In this chamber, ribs 22 are provided for defining a channel in the chamber through which any suitable cooling medium is passed. The ribs 22 are arranged to form any suitable shape of chamber. In the illustrated form, the chamber is spiral, and furthermore, is preferably made of a varying cross section. The varying cross section changes the velocity of the cooling medium, increasing such velocity at points where the cross section of the chamber is decreased, thereby effecting a better or increased cooling at such points. The varying cross section of the spiral channel in the described cylinder head is illus- 15 trated in Fig. 3, wherein the channel is considerably decreased at points 23 and 24 between the walls 5 and 6. The speed of the cooling fluid at these points is greatly increased, whereby the increased cooling effect on the valve structures is obtained.

The cooling medium enters the cylinder head at port 25, in Fig. 3, and circulates through the spiral channel, above described, and then rises 20 through a port 26 in the partition 9 into a cooling jacket formed by the outer wall 5, inner wall 6 which extends to the top plate 8 at this valve passage and a wall 27, as illustrated in Fig. 2. This cooling jacket is formed about the valve 25 passage 7 into which the outlet valve structure is placed. In this jacket, the cooling medium rises and leaves the cylinder head through an opening 28 in the top plate 8. Compared with the total height of the cylinder head, I prefer 30 to make the cooling chamber low to cause a greater velocity of the circulating cooling medium. In the present example, the height of the cooling chamber is in the order of one-third that of the head. By this circulation of cooling fluid, 35 the lower part of the cylinder head and the valve structure in passage 7 is sufficiently cooled.

The plate 8, as stated above, closes the upper 40 end of the cylinder head and thereby forms an air chamber on the right hand side of the cylinder head as illustrated in Fig. 1. This chamber is bounded by the outer wall 5, top plate 8, intermediate plate 9, and the wall 27. Air under pressure is supplied to this chamber and therefore enters the cylinder with the least pos- 45 sible loss of pressure. The air supplied to the cylinder may enter this chamber either through the openings in the top plate which register with the valve passages or it may enter through an opening 20 in the wall 5. A similar open- 50

ing 30 in the wall 5 opens into the other valve chamber through a conduit formed by the plate 9 and a surrounding wall 31. Reinforcing ribs 32 and 33 in the air chamber strengthen this upper part of the structure.

What I claim as new and desire to secure by Letters Patent of the United States, is:

1. In a cylinder head for internal combustion engines comprising an outer wall and inner walls cast together with the outer wall and defining passages for valve structures, a base plate fastened to the lower end of the head and having openings registering with said passages, a partition within the head defining with the base plate and the adjacent walls a cooling chamber, ribs in the chamber defining a channel for a cooling medium, and a top plate defining with the walls and the partition a chamber for containing fresh air.

20 2. A cylinder head for internal combustion en-

gines comprising a body and inner walls defining passages for valve structures and being cast together with the body, a base plate fastened to the body, a partition provided near the base plate for defining with the latter and the adjacent walls a cooling chamber, a jacket defining with one of the walls above the partition a cooling space communicating with the chamber, and a top plate for the head having an opening for discharging cooling medium from the space and defining with the body and a part of the jacket a chamber for containing fresh air.

3. In a cylinder head for internal combustion engines, an integrally cast structure defining the body for the head and passages for valve means, a separate base plate fastened to the structure, a partition for defining a cooling chamber near the base plate, and a top plate for defining a chamber for containing fresh air.
